SAFETY RAZOR

Louis C. Guertin, Worcester, Mass.

Application August 23, 1940, Serial No. 353,909

14 Claims.

(Cl. 30—60)

The present invention relates to a new and improved safety razor and blade therefor.

Objects of the invention include the provision of a safety razor blade of new and improved design; the provision of a razor having a construction such as to permit the blade to be set in and taken out in a quick and simple manner; the provision of a razor having a spring hinged top blade clamping member so arranged that when the clamp actuating means is released, the clamping member will automatically rise slightly from the blade and thus unclamp the same and render it safe and easy to remove the blade; the provision of a spring hinged blade clamping member as above, in which the spring will seat the clamping member on the blade upon a mere snap of the spring; and the provision of a new and improved clamp actuator for the blade clamp.

Other objects and advantages of the invention will appear hereinafter.

Reference is to be had to the accompanying drawing, in which

Fig. 1 is a front elevation of a razor embodying the present invention;

Fig. 2 is a partial side elevation of the same, looking in the direction of arrow 2 in Fig. 1;

Fig. 3 is a top plan view of the same;

Fig. 4 is a top plan with the top blade clamping member open;

Fig. 5 is a section on line 5—5 of Fig. 4;

Fig. 6 is a top plan view of the blade;

Fig. 7 is a partial view of one end of the bottom blade clamping member;

Fig. 8 is a detail view of the top blade clamp and its spring;

Fig. 9 is a sectional view showing a modified blade clamp actuator; and

Fig. 10 is a sectional view showing the blade clamping members in released condition.

Referring to the drawing in detail, numeral 10 indicates a tubular handle which may be secured to or integral with a bottom blade clamping member 12 having the usual guard teeth 14. A rod 16 extends thru the handle in a sliding manner and is provided with a fixed abutment member 18 extending transversely of the rod 16. A pair of tits 20 extend downwardly from the underside of the abutment for a purpose to be explained.

The lower end of rod 16 is threaded to engage a nut 22 as shown in Fig. 1, and this nut is provided with a reduced barrel 24 to slidably and rotatably fit in the handle 10. An annular shoulder 26 is formed on the nut at the base of the 55

barrel to provide an abutment against the open end of the handle. It will be observed that a restricted portion 28 of the handle and barrel 24 combine to locate rod 16, and that the latter 5 may be rotated and moved axially by the nut used as a handle. Of course, the nut 22 cannot be moved upon the threads on handle 16 unless something retains the rod or abutment 18 against turning, and in this case, the nut can be turned 10 up to draw the rod down, or it can be loosened to effectually lengthen the rod.

Turning to Fig. 5, it will be seen that the bottom clamping member 12 has secured to its underside adjacent one end, a thin leaf spring 30. This spring is arranged to lie as straight as is compatible with the transversely curved underside of the member 12, but in any case the spring tends to lie at rest in up position, so that if it is bent downwards at its free end, it will oppose 15 such action. A top blade clamping member 32 is provided with a pair of depending lugs 34, such lugs being apertured to receive laterally extending projections 36 on the free end of spring 30. By this means the top clamping member is 20 hinged to the bottom member 12, so that with the former in closed, but not clamped, position, the spring will cause it to be spaced from the bottom member. Also, with the parts in position as 25 shown in Fig. 5, the finger can be used to draw back slightly on the member 32, and when released, the resilience of the spring will cause this member to snap over to closed position.

Slots 38 are provided in the end of bottom member 12 for the guiding reception of the lugs 34 to render the parts more rigid and to form exact means for the closed position of top member 32. An aperture 40 in the top member provides for passage therethru of the abutment 18, and depressions 42 serve to locate and lock the abutment by means of tits 20.

The razor blade is shown in Fig. 6, and this blade comprises a pair of narrow cutting members 44, connected at their ends by strips 46, slots 48 correspond with slots 38 in the bottom member, and lugs 34 also pass into the blade slots when the razor is closed so that the blade will be locked in the desired correct position. There is also a pair of central interior slots 50 and the blade is otherwise shaped to fit the element 52 on the bottom member, which has extensions 54 to be received in slots 50. It will be seen that slots 48, 50, and element 52 will ensure correct location of the blade, and that there is therefore practically no chance for the wrong positioning thereof. If the blade is in the wrong position,

the top member 32 cannot close, due to lugs 34.

The top member 32 is provided with a raised rim 56, the sides 58 of which will pinch down on the members 44 of the blade to securely clamp the same. Depressions 60 are adapted to receive the ends of projections 54 to allow the end portions 62 of the rim to clamp the end strips 46 of the blade. Hence the blade, besides being always correctly positioned, will be positively clamped about its entire periphery.

In the operation of the device, the blade is set about the member 52, with projections 54 in slots 50, the top member 32 is snapped up in the direction of the arrow in Fig. 5 to cover the blade, with lugs 34 entering slots 38, 48; the rod 16 is turned to seat tits 20 in depressions 42, and the nut 22 is then given a turn or two to firmly clamp the parts in place against the action of spring 30. When thru shaving, the operator backs off on the nut just enough to release the abutment 18 from the top member 32, and this will allow the spring to raise the top member and loosen it from the blade; so that the latter can be easily removed without the necessity of manually forcing the top member off the bottom member and off the blade.

Fig. 9 shows a modified handle arrangement in which the rod 66 is threaded to nut 68 but is fixed thereto by a set screw 10. A coil spring 72 continually urges the rod to clamping position wherein the abutment will engage the top clamping member. To release, it is merely necessary to press nut 68 against the spring tension, and the latter can be adjusted by backing off on the set screw, turning the nut up on the rod, and again tightening the screw.

Having thus described my invention and the advantages thereof, I do not wish to be limited to the details herein disclosed, otherwise than as set forth in the claims, but what I claim is:

1. A safety razor comprising a pair of blade clamping members, a spring attached to one member, and the other member being pivoted on said spring.

2. A safety razor as recited in claim 1, in which the spring is effective to normally urge the said other member from the said one member.

3. A safety razor comprising lower and upper blade clamping members, a leaf spring attached to said lower member, said upper member having a lug, said lug being pivoted to said spring.

4. A safety razor as recited in claim 3 in which the spring is effective to normally urge said upper member from said lower member at the lug area.

5. A safety razor comprising a pair of blade clamping members, means pivotally connecting said members, said means comprising a leaf spring on one member and a lug on the other member, said lug being hinged on said spring.

6. A safety razor comprising a pair of blade clamping members, a leaf spring attached at one end to one of said members, a lug on the other member, said lug being pivoted to said spring at the latter's free end.

7. A safety razor comprising a handle, a lower blade clamping member fixed to said handle, an upper blade clamping member, resilient means to normally urge said members apart, said upper member being pivotally mounted on said means, and means movable in said handle to force said members together.

8. A safety razor as recited in claim 7 in which the last mentioned means comprises a rod axially movable in said handle, an abutment on said rod for engagement with said upper blade clamping member, and means effective to move said rod in a direction to draw said upper member into clamping engagement with said lower member.

9. A safety razor as recited in claim 7 in which the last mentioned means comprises a rod axially movable in said handle, an abutment on said rod for engagement with said upper blade clamping member, and screw means to move said rod to blade clamping position of said members.

10. A safety razor as recited in claim 7 in which said last mentioned means comprises a movable rod, an abutment on said rod for engagement with said upper member, and spring means to move said rod to blade clamping position of said members.

11. In a safety razor, the combination of a pair of blade clamping members, pivot means for said members comprising a pair of depending lugs on one member and a hinge element on the other member cooperating with said lugs; with a razor blade adapted to be secured between said blade clamping members, and guide slots in said blade to receive said lugs in cooperative relation therewith, whereby said blade will be correctly positioned between said blade clamping members during their closing and holding operations.

12. In a safety razor, the combination of a pair of pivoted blade clamping members, said members being relatively movable, and cooperating guide means between said members adjacent the pivot; with a blade having slots adapted to also cooperate with said guide means, whereby both members and said blade may be correctly relatively positioned during the closing and clamping actions of said blade members.

13. In a safety razor, the combination of a pair of pivoted blade clamping members, a raised element centrally located on one member, a peripheral rim on the other member, said element extending into the rim when the razor is closed, thus forming a peripheral clamping surface at said rim, and guide means for said members during their closing action; with a razor blade having a narrow peripheral rim and a central aperture so as to fit over said raised element, said blade rim being adapted to be clamped by the rim on said other element, and means on said blade cooperating with said guide means.

14. A razor blade comprising a body having a large generally rectangular aperture centrally thereof, said aperture forming narrow cutting members at the longitudinal edges of said body and end strips connecting said members, said end strips each having a pair of spaced guide slots opening exteriorly of said body and a central interior locating slot, said guide slots being adapted to guide blade clamping elements of a safety razor in their closing movement and said locating slot being effective to cooperate with a lug on one blade clamping member for initial positioning thereon of said blade, whereby said blade may be located on said one member and thereby act as a part thereof so that said guiding slots may effectively carry out their guiding function.

LOUIS C. GUERTIN.
